UNITED STATES PATENT OFFICE.

THOMAS SPENCER MILLER, OF SOUTH ORANGE, NEW JERSEY, AND LOUIS G. RUGGLES, OF NEW YORK, N. Y., ASSIGNEES OF ONE-HALF TO LIDGERWOOD MANUFACTURING COMPANY, A CORPORATION OF NEW YORK.

HOISTING-ENGINE.

1,252,473.

Specification of Letters Patent.

Patented Jan. 8, 1918.

Original application filed June 3, 1913, Serial No. 771,399. Divided and this application filed July 3, 1915. Serial No. 37,894.

To all whom it may concern:

Be it known that we, THOMAS SPENCER MILLER and LOUIS G. RUGGLES, citizens of the United States, and residents, respectively, of South Orange, in the county of Essex, State of New Jersey, and New York city, borough of Manhattan, in the county of New York, State of New York, have invented certain new and useful Improvements in Hoisting-Engines, of which the following is a specification.

This application is filed as a division of our prior application filed June 3, 1913 and Serial Number 771,399.

15 Our invention relates to new and useful improvements in hoisting engines for operating the ropes of hoisting and load transferring apparatus generally, and particularly contemplates a hoisting engine adapted 20 for use in connection with rope systems employing a plurality of ropes, for instance two, and wherein it is desirable to operate the ropes simultaneously or independently of each other.

25 A further object is to provide a hoisting engine which will embody a plurality of drums each provided with its individual actuating engine or motor, which may be driven to operate said drums simultaneously 30 or independently of each other, and in which the actuating engines or motors may have the power thereof combined to act as the driving means for one of or either of the drums.

35 In accomplishing the above object we prefer to employ a plurality of drums each having its own individual driving engine or motor, and connect each drum with its engine or motor by an individual drive connection, 40 whereby the drums are individually driven, and also provide means for connecting the individual drum driving means, whereby both the drums will be simultaneously driven and the power of both engines or 45 motors may be exerted upon one of the drums.

The invention consists in improvements to be more fully described hereinafter, and the novelty of which will be particularly pointed out and distinctly claimed.

50 We have fully and clearly illustrated our invention in the accompanying drawings, to

be taken as a part of this specification, and wherein—

Figure 1 is a top plan view partly in section of a preferred embodiment of our invention.

Fig. 2 is a view in side elevation of the structure shown in Fig. 1.

Fig. 3 is a detailed top plan view partly in section of a coupling means for connecting the motors for driving the drums shown in Fig. 1, so that both motors or engines may exert their power upon one of the drums.

Referring to the drawings by characters of reference 30, 31 designate hoisting drums 65 mounted respectively on suitable shafts 32, 33, preferably arranged in longitudinal alignment and journaled in the side frames 36 and the intermediate member 37 of the bed-plate of the engine structure. In the 70 preferred embodiment the drums 30, 31 are keyed or otherwise rigidly fixed to the shafts 32, 33, and each drum carries a driving gear shown respectively at 34, 35. Extending parallel with the axis of revolution of the 75 drums 30, 31 are two driving shafts 38, 38 arranged in longitudinal alignment and having bearing at their outer ends in pedestals 39, and at their inner ends in said intermediate frame member 37. Each of these shafts 38, 80 38 carries a driving pinion 40, said pinions meshing respectively with the gears 34, 35 heretofore described, said shafts 38, 38 also carrying larger gears 41 which mesh respectively with driving gears 42, 42 on the 85 longitudinally alining armature shafts 43 of electric motors 44 which are preferably of a reversible type. The opposite ends of the armature shafts from the ends carrying the gears 42 are each provided with a friction 90 disk or brake wheel 44^a with which co-operates suitable brake mechanism 45 operated by a solenoid 46 to positively grip and hold the armature shafts against rotation. Each of the said motors is provided with its own 95 individual controller 47, the controller for each motor being independent of that for the other motor, and each including a rotary hand-operated shaft 48 adapted to be operated by a hand lever 49 to control the supply of current to its motor. We do not deem it

necessary to describe specifically the con-

- struction and operation of the controllers as they may be of any type suitable for the purpose, but desire to state that they are preferably of the type wherein an intermediate position of the hand-operating lever 49 cuts off supply of current to the motors, while forward movement of said lever causes a supply of current to be thrown onto the motors to run them in one direction, while 10 the rearward movement of the lever from intermediate position serves to reverse the motors. It will be seen that by the construction just described the motors are independently controllable to drive the drums independently of each other, so that the drums may be driven in the same or opposite directions, or one may be at rest while the other is being driven.

Referring particularly to Fig. 1 of the drawings, it will be seen that the controller operating shafts 48 are arranged in longitudinal alinement with each other, and are provided at their inner or adjacent ends with coupling extensions 50 having poly-faced ends 51 adapted to be connected by a coupling sleeve 52 provided with a tightening screw 53 adapted to engage one of said extensions to lock the sleeve in position, either to couple the coupling extensions, or 25 when said extensions are disconnected, to secure the sleeve to the extension carrying the same. It will be understood that this sleeve 52 is movable lengthwise of said shafts to couple them together to cause the controllers to be simultaneously operated, or 30 said coupling may be moved in the opposite direction to disconnect the controller shafts 50 from each other so that said controllers may be independently operated for the purpose above set forth.

We preferably employ electric motors of a type capable of dynamic braking; that is which, when over-speeded, generate current to retard rotation of the armature. This 45 type is desirable because the motor operates automatically to retard rotation of the drum driven thereby when there is a tendency of the load on the drum to over speed the same.

We provide means for connecting and disconnecting two of the longitudinally alining elements heretofore described, so that the power of both motors may be exerted to drive one of the drums when power in excess of that of one of the motors is desired, said 50 connecting and disconnecting means being preferably applied to the longitudinally alining armature shafts, as will now be described: Mounted on one of the armature shafts 43 is an internally toothed clutch member 54, preferably fixed to this armature shaft against movement longitudinally thereof, while upon the opposite and alining armature shaft is an externally toothed clutch member 55, movable longitudinally 55 of its shaft by a suitable operating means

56 to engage within, or be withdrawn from the member 54. It will be understood that when the member 55 is projected into the member 54 both armature shafts will be connected so that both motors may exert 70 their power upon one of the drums, and when the elements 54 and 55 are disconnected each motor runs its drum independently of the other motor.

What we claim and desire to secure by Letters Patent of the United States is:—

1. In combination, two winding drums, two reversible motors respectively driving said drums independently of each other, means for coupling said motors, independent 80 controllers for the motors, and means for coupling said controllers.

2. In combination, two winding drums, two shafts for driving said drums, a motor for driving each shaft, clutch means for 85 connecting said shafts, individual controllers for the motors, and means for connecting said controllers for simultaneous operation.

3. In combination, two winding drums, a motor for driving each drum, gear connections between each motor and its drum, whereby said drums are individually driven, means for coupling said gear connections whereby the power of both motors may be exerted on one of the drums, individual controllers for the motors, and means for connecting said controllers for simultaneous 95 operation.

4. In combination, a plurality of winding drums, a motor for driving each of said 100 drums, a controller for each motor, means for coupling the motor shafts whereby the power of both motors may be applied to one of the drums, and means for connecting the controllers whereby the latter may be 105 simultaneously operated.

5. In combination, a plurality of winding drums, a motor for driving each of said drums, a controller for each motor, coupling clutch members respectively on the motor 110 shafts whereby said motors may be connected to drive one of the drums by all of the motors, and means for connecting all of the controllers whereby they may be simultaneously operated to control the motors.

6. In combination, a plurality of winding drums, a motor for driving each of said drums, means for connecting said motors whereby they may all be used to drive one of the drums, a controller for each of the 120 motors, a controller shaft for each controller, and means for connecting the controller shafts whereby the controllers may be simultaneously operated when the motor shafts are coupled.

7. In combination a plurality of winding drums, a motor for driving each of said drums, clutch means for connecting the motor shafts whereby one of the drums may be driven from all of the motors, a con- 130

5 troller for each motor, each of said controllers having a controller shaft provided with an operating lever, and means for connecting the controller shafts whereby they may be simultaneously operated by one of said operating levers to control the motors when they are coupled.

8. In combination, two winding drums arranged to rotate on axes in longitudinal alinement with each other and each provided with a gear, two prime movers having individual power shafts in longitudinal alinement with each other, and each carrying a gear, shafts between the power shafts and the drums and geared to the drum gears and the gears on said power shafts, said shafts between the power shafts of the drums be-

ing in longitudinal alinement, means for connecting and disconnecting two of said rotatable elements in longitudinal alinement 20 with each other, individual controlling means for each of said prime movers, and means for connecting and disconnecting said controlling means whereby they are capable of simultaneous or individual operation. 25

In testimony whereof we have hereunto signed our names in the presence of two subscribing witnesses.

THOMAS SPENCER MILLER.
LOUIS G. RUGGLES.

ERNEST PULSFORD,
C. K. MACALPINE.

It is hereby certified that Letters Patent No. 1,252,473, granted January 8, 1918, upon the application of Thomas Spencer Miller, of South Orange, New Jersey, and Louis G. Ruggles, of New York, N. Y., for an improvement in "Hoisting-Engines," were erroneously issued to the inventors, said Miller and Ruggles, and the Lidgerwood Manufacturing Company as assignee of one-half interest in said invention, whereas said Letters Patent should have been issued to the first-named inventor, said *Thomas Spencer Miller and Lidgerwood Manufacturing Company, said corporation being assignee of the interest of said Ruggles only*, as shown by the record of assignments in this office; and that the said Letters Patent should be read with this correction therein that the same may conform to the record of the case in the Patent Office.

Signed and sealed this 19th day of March, A. D., 1918.

[SEAL.]

R. F. WHITEHEAD,
Acting Commissioner of Patents.
